(57) **CLAIM**

The ornamental design for a fireworks rocket packaging, as shown and described.

DESCRIPTION

FIG. 1 is a front elevational view of a fireworks rocket packaging showing my new design, the rear elevational view being a mirror image;

FIG. 2 is an enlarged front elevational view of the rocket motor encasing portion of the packaging of FIG. 1 with the guide stick encasing tube foreshortened, the rear elevational view being a mirror image;

FIG. 3 is an enlarged right side elevational view of the rocket motor encasing portion of the packaging of FIG. 1 with the guide stick encasing tube foreshortened, the left side being a mirror image thereof;

FIG. 4 is an enlarged top plan view;

FIG. 5 is an enlarged bottom plan view; and,

FIG. 6 is an enlarged right side perspective view of the rocket motor encasing portion with the guide stick encasing portion foreshortened.

The tube portion is shown broken away to indicate indeterminate length.
